UNITED STATES PATENT OFFICE.

HERMAN HENCKLER AND WILLIAM J. EICKS, OF ST. LOUIS, MISSOURI.

MUSIC-LEAF TURNER.

SPECIFICATION forming part of Letters Patent No. 594,625, dated November 30, 1897.

Application filed February 5, 1897. Serial No. 622,198. (No model.)

To all whom it may concern:

Be it known that we, HERMAN HENCKLER and WILLIAM J. EICKS, citizens of the United States, residing at the city of St. Louis, in the 5 State of Missouri, have invented a certain new and useful Improvement in Music-Leaf Turners, of which the following is a full, clear, and exact description, reference being had to the accompanying drawings, forming a part of 10 this specification.

Our invention relates to a device for employment in turning sheets of music, the device being arranged to be supported in a suitable position convenient for a performer upon 15 a musical instrument of any description. It is more particularly designed for employment in connection with a piano or similar instrument or violins.

Our invention consists in features of novelty 20 hereinafter fully described, and pointed out in the claims.

Referring to the drawings, Figure I is a front elevation of our improved turner. Figs. II and III illustrate a cross-section, taken 25 through the music sheet or book holding clamp, Fig. II showing the clamp closed and Fig. III showing it open for the insertion of the music sheet or book. Fig. IV is a detail front elevation of the leaf-turning-arms-operating mechanism. Figs. V and VI illustrate 30 a section taken on line V VI, Fig. IV, Fig. V showing a portion of the leaf-carrying arms in tripped position and one of the arms in untripped position and Fig. VI showing all of 35 the arms in untripped position. Figs. VII and VIII illustrate a vertical section taken on line VII VIII, Fig. IV, Fig. VII illustrating all of the leaf-carrying arms in untripped position and showing all of the pawls of the leaf-carrying arms in untripped position, the upper 40 pawl being shown in process of tripping, and Fig. VIII showing only the lower pawl in untripped position. Fig. IX illustrates a vertical section, taken on line IX IX, Fig. I, 45 through the lower end of the clamp. Fig. X is a detail edge view of the outer end of one of the leaf-turning supporting-strips. Fig. XI is a detail view of the pawl-operating rod and its adjusting-spring. Fig. XII is a detail 50 edge view of the inner end of one of the turner-supporting strips and the bar to which it is

connected. Fig. XIII is a detail side elevation of the pawl-operating trip rod and lever. Fig. XIV is a detail edge view of one of the pendent arms carried by the leaf-turning 55 arms. Fig. XV is a perspective view of the sheet-retaining-arm pawl and a fragment of its supporting-arm, together with a fragment of its retaining-stop. Fig. XVI is an under perspective view of one of the spring-containing barrels, the pawl-carrying arm carried thereby, and the pawl pivoted to said arm.

In the drawings, 1 designates the back of the leaf-turner, on which the music-clamp and turning mechanism are mounted. Any suitable means of supporting the device may be employed; but for the purpose of attaching it to a piano or similar instrument we have shown a pair of straps designed to engage the music-holding rack of the instrument. 70

2 designates the straps, which are connected to a bar 3, attached to the back 1, the means of connection employed being a set-screw 4, passed through slots 5 in the straps and entering said bar 3. This arrangement provides for the extension or contraction of the straps relative to the back 1 for the purpose of adapting the attachment of the device to music-racks of varying widths. The outer ends of the straps 2 are bent inwardly and 75 receive rods 6, provided with knobs 7 and carrying on their inner ends cushioned plates 8, held forward by coiled springs 9, surrounding the rods 6. These plates engage the edges of the music-rack and are released from engagement by grasping the knobs 7 and drawing outward upon them. 80

10 designates spring-clips, each secured at one end to its strap 2 and having the free ends arranged to receive and hold the edges 90 of the cover of a music-book.

11 designates a clamp for holding the music book or sheet by engaging its rear edges. This clamp is composed of members 12 and 12^a, one of which is provided with a finger-piece 13. The rear edges of the members 12 and 12^a are curved inward and outward and bear against pivot-studs 14 on the inner faces of brackets 15, mounted on the back 1. Intermediate of the ends of the clamp 11 we provide the member 12 with a slotted lug 16 and the member 12^a with a lug 17, provided with 95 100

a pin 18, that operates in the slot of the lug 16. The free end of a spring 19, secured to the back 1, bears upon the lugs 16 and 17 and tends to depress them, and in so doing holds 5 the outer edges of the clamp members together, in which position the clamp retains the book or sheet-music inserted in the clamp. To enable the insertion of the book or music-sheet, the finger-piece 13 is pressed inward 10 and the lug 16 is moved outward, carrying with it the lug 17 and the members of the clamps pivoted on the studs 14, the spring 19 closing the clamp on the release of the finger piece 13. On the inner sides of the clamp 15 members are stop-bars 20, that limit the extent of insertion of the music sheet or book.

21 designates a plate removably mounted upon the upper end of the back 1 by means of socket-pieces 22, that engage the edges of 20 the back 1 and are held by spring-catches 23, that permit the withdrawal of the socket-pieces. On the plate 21 is an upright 24, provided with recesses 25, that receive buffer-springs 26. At the upper end of the upright 25 24 is an extension 27, provided with a slot 27^a, that receives the upper end of a trip-rod 28. The trip-rod 28 is pivotally connected at its lower end to an operating-lever 29, provided with a finger-plate 30 and pivoted to a bracket 30 31, secured to the back 1. The trip-rod 28 operates through the free end of a spring 32, secured to the back 1, and near its upper end it carries a prong 28^a. The outer end of the operating-lever 29 is held in an elevated 35 position by a spring 33.

34 designates stops on the inner face of the upright 24. These stops are laterally offset from each other, each succeeding stop being located to the rear of a vertical line from the 40 one next above it, and each stop is provided with a rear inclined face 35.

36 designates an arbor rigidly seated in the plate 21. On this arbor are mounted, one above another, a series of barrels 37, each 45 containing a spring 38, one end of which is attached to the arbor and the other end attached to the barrel. Each barrel 37 carries an arm 39, and each arm has a pendent arm 40 pivoted to its outer end. Each of the pendent arms 40 is provided with a spring-clip 41, composed of two plates, on the opposing faces of which are nibs 42, that engage the music-sheet to be turned. (See Fig. XIV.) On the barrels 37, approximately opposite the 55 arms 39, are arms 43, and pivoted to these arms 43 are pawls 44, whose rear ends rest in contact with the free ends of springs 45, secured to the arms 43. (See Figs. IV, XV, and XVI.) The pawls 44 are arranged to ride 60 over the inclines 35 of the stops 34, and on passing the stops the springs 45 return them to normal position, when they engage the forward face of the stops and are held from movement until released by the movement of the trip-rod 28, as will appear in the reference to the operation of the device.

46 designates a case that incloses the spring-containing barrels 37 and the adjacent portions of the device. This case is provided with slots 47, in which the arms 39 operate. 70

In the operation of this device the leaf-turning arms 39 are placed in the position shown in Fig. I, and the pendent arm 40 of each arm 39 is connected to a music-sheet by means of the clip 41, the upper and longest 75 arm 39 being connected with the outermost sheet and the other arms being connected with the successive sheets in order to the lowermost arm. With the arms in the position as specified the pawls 44 are held in engagement with the stops 34, as illustrated in Fig. IV. Now on depression of the operating-lever 29 by pressure upon the finger-plate 30 the trip-rod 28 is moved and the prong 28^a, coming in contact with the uppermost pawl 80 44, elevates the pawl against the action of its controlling-spring 45 and it is released from engagement with the stud 34. The pawl becoming released within the uppermost barrel 37 causes the barrel to be turned, and the 85 arm 39, carried by it, is swung to the opposite side of the device into the position illustrated in dotted lines in Fig. I, at the end of which movement the arm 39 comes in contact with its respective buffer-spring 26 and is 90 stopped. After the uppermost pawl has been released the spring 32 carries the trip-rod 38 rearwardly in the slot 27^a of the extension 27, where it is in position to engage with the succeeding pawl on the operation of the lever 95 29 and the tripping of the succeeding pawl, the same as in the first instance. The same action proceeds until all of the arms 39 have been released, when the device may recede by turning the arms back to their original 100 position, in which action the pawls 44 ride over the stops 34 and engage therewith, as before mentioned.

We claim as our invention—

1. In a leaf-turner, the combination of a 110 support, spring-containing barrels mounted on said support, sheet-turning arms carried by said barrels, a support provided with stops, pawls carried by said barrels arranged to engage said stops, and means for tripping said 115 pawls, substantially as described.

2. In a leaf-turner, the combination of a support, spring-containing barrels mounted on said support, sheet-turning arms carried by said barrels, a support provided with stops, 120 said stops being provided with inclined rear faces, spring-controlled pawls carried by said barrels arranged to ride over said inclined faces and engage said stops, and means for tripping said pawls, substantially as described.

3. In a leaf-turner, the combination of a support, spring-containing barrels mounted on said support, sheet-turning arms carried by said barrels, a support provided with stops, 130 spring-controlled pawls carried by said barrels, a trip-rod carrying a prong adapted to

engage said pawls, and an operating-lever connected to said trip-rod, substantially as described.

4. In a leaf-turner, the combination of a support, spring-containing barrels mounted on said support, sheet-turning arms carried by said barrels, an upright, stops offset from each other on said upright, spring-controlled pawls carried by said barrels, a trip-rod arranged to engage said pawls, a spring arranged to press said trip-rod into engagement with said pawls, and means for operating said trip-rod, substantially as described.

5. In a leaf-turner, the combination of a support, a clamp composed of two members

separately pivoted to said support, lugs arranged on the inner sides of said members opposing and contacting with each other, a spring arranged to hold said members together, one of said members being provided with a finger-piece on the depression of which the lug carried by its member is caused to operate the opposing lug and cause the clamp members to be opened simultaneously, substantially as described. 20
